UNITED STATES PATENT OFFICE.

JAMES BRADY, OF BROOKLYN, NEW YORK.

MACHINE FOR STRETCHING BELTING.

SPECIFICATION forming part of Letters Patent No. 251,824, dated January 3, 1882.

Application filed October 26, 1881. (No model.)

To all whom it may concern:

Be it known that I, JAMES BRADY, of Brooklyn, Kings county, New York, have invented certain new and useful Improvements in Stretching Leather Belting, of which the following is a specification.

My present invention may be described as an improvement on the system of stretching belting set forth in a former patent reissued to me January 27, 1880, No. 9,059. In this patent the belting to be stretched is first wound upon a drum or delivery-roll and thence passed over a series of rollers arranged in zigzag order, termed "flexion" and "reflexion" rollers, and finally winds upon a second drum or receiving-roll. Power is applied to revolve the receiving-drum, while a brake or resistance is applied at the delivery-drum to retard the unwinding of the belt therefrom, so that the rotation of the receiving-drum winds in the belting, unwinding it from the delivery-drum and drawing it in flexing and reflexing bends over the zigzag series of rollers, which action subjects the belting to a strong lengthwise strain, as well as to a lateral bending and rebending, which effectually stretches both the strong and weak parts of the belt, and thus uniformly extends the whole fabric. In this system of stretching it will be noted that the stretching is performed at one action, or is completed when the belt is wound from the delivery-roll onto the receiving-roll, and during this single action the belt is subjected to considerable strain. Now, according to my present improvement, I keep the belt in continued or repeated motion, preferably over a series of flexion and reflexion rollers, either in a to-and-fro course or in a regular circuit, maintaining on the belt at the same time a slight tension, whereby the stretching action is more gentle but long continued, and the belt becomes stretched mainly by the flexion and reflexion during its continued motion, assisted by the slight tension applied thereto, which tension acts mainly to take up the slack or extension formed during the continued bending and rebending movement of the belt, which mode constitutes the main feature of my present improvement, as hereinafter fully set forth.

In the annexed drawings, Figure 1 presents a sectional side elevation of a machine adapted to carry out my present improvement and

forming part of my invention. Fig. 2 is a plan view of this machine, and Fig. 3 illustrates a modification.

In Figs. 1 and 2, *a a* indicate the two sides of a strong frame, which are affixed rigidly together by the tie rods *b b*. At each end of the frame is journaled a large drum, *c c*, and between the drums is journaled a zigzag series of flexion and reflexion rollers, *d d*, similar to those in my previous patent, which drums and rollers are free to revolve in their bearings in the side frames, *a a*, as will be understood. At one or both ends of the series of flexion rollers, or at any other suitable position, is arranged a movable tension or take-up roller, *e*, which is preferably journaled on the ends of swinging levers *g g*, forming a swinging or movable frame, which is connected by the chain *h* with the shaft of a small windlass, *f*.

i indicates the belting to be stretched, which is usually made in lengths of five hundred feet, and according to my present system this belt is preferably joined at the ends by lacing or suitable hooks, as shown at *k*, so as to form an endless belt or band, which is wrapped around the two drums *c c* and passed over the several flexion-rollers, *d d*, and also around the take-up roller *e*, as fully shown in Figs. 1 and 2. Now, over one or both of the driving-drums *c c* is mounted a gripe-roller, *l*, which is journaled in a suitable hinged frame or lever, *m*, provided with an adjustable weight, *m'*, whereby the roller is constantly pressed against the belt, forcing the latter closely against the drum *c*, and thus greatly increasing the bite or frictional adhesion between the belt and the drum, and thereby increasing the driving power of the drum on the belt. Now, the shaft of each driving-drum is provided with the fast and loose pulleys *o o'*, (shown in Fig. 2,) whereby power may be applied to revolve both drums in similar directions, as illustrated, which revolution will of course move the belt over the several rollers *d d*, and the take-up roller *e*, and keep the same in a constant circuit through the machine. While the belt is thus kept in motion the take-up roller *e* at the same time constantly tends to move outward by reason of the pull of the suspended weight or weights *t*, which tend to revolve the drum in a direction to wind in the chain *h*, and thus move out the frame *g g* and take-up roller *e*, which acts

to constantly keep the belt taut and to take up any slack or stretch which may form therein, and at the same time maintains a slight lengthwise tension on the belt, which may be increased, if desired, by adding weights at *t* or by turning the windlass by the hand crank *u*. As the motion of the belt is thus continued the repeated bending of all its parts in opposite directions as it passes over the several drums and rollers, together with the slight lengthwise tension thereon, will eventually stretch the belt to its utmost at all parts and render it supple throughout, thus rendering the belting better for practical use, for when a piece of the belting is now cut and fitted to its pulleys it will hug the pulleys more closely and move with greater ease thereon on account of its greater suppleness or flexibility, and, furthermore, it will not stretch apparently and become loose when run for some time, as would be the case with a stiff unstretched belt. It may therefore be now noted that by my present improved system of stretching, the operation is performed in a gradual and gentle manner, without putting much strain on the belt, and hence having no tendency to appreciably displace the fiber or strain the texture of the belt, but the stretching and softening of the belt are performed, as it were, in a more natural or long-continued manner, rather than sudden and forced, as heretofore. Furthermore, in the present apparatus, after the belt is placed in position and the machine started it requires no further attention and may be left running for hours, or until the belt is sufficiently stretched, which will be indicated by the advanced position of the take-up roller in its slot, and after a given time, with a certain tension on the belt, when the roller refuses to further advance, this will indicate that the belt is sufficiently stretched. Hence it is readily apparent that the stretching action of the present machine upon the belt is of a perfectly natural and safe character, instead of being positive and forcible. Furthermore, while one length of belting is being stretched in the machine the workmen may be engaged in cementing and riveting another length, and by the time the second length is ready to be stretched the first length may be removed from the machine and rolled up, ready for the market, without requiring any attention from the workmen in the meantime. Again, in some cases, the motion of the take-up roller, when it has advanced out sufficiently far, may act to sound an alarm to call the attention of the workmen or operate a trip to stop the machine, thus rendering the machine entirely automatic.

It will be observed from Fig. 2 that the drums and rollers are sufficiently long to suit the widest belt, and that the driving-drums *c* are provided with adjustable rims *c' c'*, which may be moved in or out, so as to approach opposite edges of the belt, whether wide or narrow,

and at the same time keep the belt always in the middle of the machine. It is much preferable that the belt should be joined into an endless band and moved in a continued circuit through the machine, as described and shown, but it is not essential, for the belt may be left separate at the ends and moved in a to-and-fro course, as represented in Fig. 3. In this case a pair of gripping-rollers, *v v*, are arranged at each end of the series of flexion-rollers *d d*, power being applied to one pair to move the belt, while the second pair are adjusted to a lighter gripe than the driving pair, so as to partly retard the belt and thus put a slight lengthwise tension on the belt as it is pulled onward by the driving-rollers. When the belt is moved through the machine to the limit of its length in one direction the action of the rollers *v v* is reversed and the belt moved back again, this to-and-fro motion being repeated till the belt is sufficiently stretched, as will be understood.

I might note that stationary bars might be used as an equivalent for the rollers *d* and *e*, over which the belt would be drawn with the same effect as in the case of rollers, but with a greater friction and strain, which renders rollers far preferable.

What I claim is—

1. The specified mode of stretching belting, consisting in submitting the belting to a repeated or continued motion over rollers or supports while under a continuous regulated tension, whereby the belt is kept uniformly taut, substantially as herein shown and described. 95
2. The specified mode of stretching belting, consisting in joining the belt in the form of an endless band and keeping this band in motion over rollers or supports while under a continuous regulated tension, substantially as 100 herein shown and described. 105
3. A machine for stretching belting while in the form of an endless band, consisting of a driving drum or pulley over which one loop of the belt is passed, in combination with a movable tension or take-up roller or bar over which another loop of the belt is passed, and means for advancing said roller to render the belt taut and take up the slack or stretch therein, and a suitable supporting-frame for said parts, substantially as herein shown and described. 110 115
4. In a machine for stretching belting, the combination, with a driving drum or pulley to keep the belt in motion, of a series of flexion and reflexion bars or rollers over which the belt passes in bends from the driving-drum, and one or more movable take-up or tension rollers over which a loop of the belt passes in its course, substantially as and for the purpose set forth. 120
